WINDOW CURTAIN

Morton A. London and Herbert I. London,
Philadelphia, Pa.

Application October 20, 1951, Serial No. 252,339

8 Claims. (Cl. 160—349)

1

This invention relates generally to draped window curtains and is more particularly concerned with an improved tie-back construction therefor affording particular advantage as to the manufacture, maintenance and appearance of such a curtain.

One class of draped window curtains is characterized by a tie-back construction forming an integral part of the curtain, and in such class it is common to sew opposed end portions of a draw member and a strip of fabric to the inner edge of the body portion of the curtain, from whence they are extended transversely across the body portion or panel to the outer edge thereof, the strip of fabric being sewed to the panel to form therewith a pocket through which the draw member extends freely. Certain disadvantages are inherent in this known construction. One disadvantage is that in assembling the parts of the curtain the operator must handle the strip of pocket forming fabric separately from the draw member, which tends to make the cost of manufacture higher than it would otherwise be. Another disadvantage is that dirt tends to lodge in the pocket for the draw member, thus making laundering difficult. Still another disadvantage is that if the draw member does not lie flat between the strip of pocket forming fabric and the panel, it is difficult to iron the material in the proximity of the pocket, and on the other hand, if the draw member does lie flat, it is difficult to straighten it out when it becomes twisted, and it is impossible to iron the full length thereof. And still another disadvantage is that when it becomes necessary to replace the draw member, the stitches securing the strip of pocket forming fabric to the inner edge of the panel, as well as those securing the draw member thereto, must be removed. In addition, when the curtain is drawn up, the strip of pocket forming fabric is gathered on one side of the draw member and the panel on the other, thus the bulk of the strip of pocket forming fabric resists or works against graceful folding of the panel and tight drawing thereof.

Accordingly, it is an object of this invention to provide a window curtain with a tie-back construction wherein the draw member and the guide means therefor may be handled as a unit during the assembly thereof with the body portion or panel of the curtain.

Another object of this invention is to provide a window curtain having such a tie-back construction and characterized by freedom from pockets wherein dirt may lodge.

Still another object of this invention is to pro-

2

vide a window curtain having such a tie-back construction and characterized by a guide means having an open construction which facilitates straightening the draw member and/or ironing it throughout its full length.

And still another object of this invention is to provide a window curtain having such a tie-back construction and characterized by a draw member which may be replaced without any necessity for disturbing the guide means therefor.

And another object of this invention is to provide a window curtain with a tie-back construction wherein when the curtain is drawn up there is no gathering of material on one side of the draw member which resists graceful folding of the curtain on the other side, or to resist drawing the curtain tight enough to give a novel draped appearance.

Other objects and advantages of the present invention will appear more fully hereinafter, it being understood that the present invention consists in the combination, construction, location and relative arrangement of parts, all as will be more fully described hereinafter, as is shown in the accompanying drawings and will be pointed out in the appended claims.

In the accompanying drawing:

Figure 1 is an elevational view of a window curtain installation showing an illustrative use of draped curtains provided with a tie-back construction incorporating the present invention;

Figure 2 is an elevational view of an illustrative embodiment of the present invention, the improved curtain being shown in a flat position with the tie-back inoperative;

Figure 3 is a view similar to Figure 2, but showing the curtain gathered at its mid portion by the tie-back;

Figure 4 is an enlarged cross-sectional perspective view of a portion of the tie-back arrangement, this view being taken substantially along the line 4—4 of Figure 2;

Figure 5 is an enlarged view showing the construction of the guide means for the draw tape, the latter being shown assembled therewith for convenient handling as a unit;

Figure 6 is an enlarged cross-sectional view showing the tie-back in use, this view being taken substantially along the line 6—6 of Figure 3; and

Figure 7 is a fragmentary elevational view of the curtain showing a modified tie-back arrangement employing a pair of draw tapes.

Referring to the drawings, it will be seen that curtains 10 and 11 are identical in construction

except that they are right and left hand, as will be obvious. A description of curtain 10, therefore, will suffice for a disclosure of any invention.

The curtain 10, as is clearly shown in Figure 2, comprises a body portion in the form of a panel 12 which is made of flexible material, and which has secured to its top a valance 13 provided with a channeled portion 14, the latter having a curtain rod 16 passed therethrough. The inner vertical edge 17 and the bottom edge 18 of the curtain 10 are shown provided with an ornamental ruffle or fringe 19, while the outer vertical edge 21 of the curtain 10 is shown without a ruffle.

Across a mid portion of the panel 12 extends an elongated tie-back construction 22 comprising a warp knitted band of material 23 and a draw tape 24. The band 23 comprises a pair of spaced parallel runs of material or headings 26-26 each formed by a warped strand alternately making a series of short loops 27 and then a pair of long loops 28, each pair of the latter constituting a transverse run of material that is disposed to extend across to an opposed portion of the other heading, overlying the opposed portion for securement thereto by three parallel runnings of chain stitched strands 29, the headings 26-26 and the spaced pairs of long loops 28 thereby forming an open ladder-like structure. The draw tape 24 is rove through the openings between the aforementioned spaced pairs of long loops 28 so that the latter alternately overlie opposite faces of the draw tape, as clearly shown in Figure 5.

The band 23 is secured to the panel 12 by lines of stitches 30-30 along the full length of headings 26-26, and the inner end portion of draw tape 24 may be secured to the inner edge of panel 12 by the same stitches that secure the ruffle 19 thereto.

The draw tape 24 is of such a length that it protrudes outwardly beyond the outer edge 21 of panel 12. By pulling on this protruding free end of the draw tape 24, the panel 12 and all of the warp knitted band 23 except the long loops 28 which overlie the outside face of draw tape 24 are gathered or folded on one side of draw tape 24, while the long loops 28 which overlie the outside face of draw tape 24 are gathered on the other side thereof.

In use, the curtain 10, after being hung, is adjusted by means of the draw tape 24 until the desired effect is obtained, after which the draw tape 24 may be secured to a suitable fastening device 32 in order to cause the curtain to hang with its outer edge 21 in a vertical position, or if free hanging of the curtain is desired, the securing may be dispensed with while the gathering is, nevertheless, retained.

If desired, a strip of ornamental material 31 may be disposed between the tie-back construction 22 and the panel 12, the warp knitted band of material 23 being sewed to the panel 12 through the ornamental strip of material 31, as best shown in Figure 4, and in such case it will be noted that the ornamental strip of material 31 folds on one side of draw tape 24 with panel 12 and all of the warp knitted band 23 except the long loops 28 which overlie the outside face of draw tape 24, while the long loops 28 which overlie the outside face of draw tape 24 are gathered on the other side of draw tape 24, as best shown in Figure 6. Also, if desired, the strip of ornamental material 31 may be disposed on one side of the panel 12, while the tie-back con-

struction 22 is disposed on the other side thereof, and in this case, too, the ornamental strip of material 31 folds on one side of draw tape 24 with panel 12 and all of the warp knitted band 23 except the long loops 28 which overlie the outside face of draw tape 24, while the long loops 28 which overlie the outside face of draw tape 24 are gathered on the other side of draw tape 24.

In assembling the parts of the curtain, the operator may handle the tie-back construction 22 as a unit since the warp knitted band of material 23 can be furnished with the draw tape 24 already rove in place. Also, it will be seen that the open construction of the warp knitted band of material 23 dispenses with pockets in which dirt might lodge, which makes applicant's arrangement desirable from the standpoint of laundering. The open construction of the warp knitted band of material 23 is also desirable from the standpoint of ironing and straightening out the draw tape 24 when it becomes twisted. With regard to ironing, since the draw tape 24 is flat there is no undue bulk to prevent proper ironing of the material in the proximity of the tie-back construction 22. In addition, the open construction of the warp knitted band of material 23 facilitates straightening out the draw tape 24 throughout its entire length when it becomes twisted. Thus, it is possible to iron the draw tape 24 in place, and, if desired, it may be separated from the warp knitted band of material 23 by pulling it through at the inner edge 17 of panel 12, ironed throughout its entire length, and then replaced.

It will be seen that due to the open construction of the warp knitted band of material 23 and the fact that the headings 26-26 thereof are secured to the panel 12 by stitches which are separate from those securing the inner end portion of draw tape 24 to the inner edge 17 of panel 12, the draw tape 24 may be replaced without disturbing the warp knitted band of material 23.

It will also be seen that since there is never any bulk of material on one side of the draw tape 24, there is no resistance to graceful folding of the material on the other side. In this connection, it will be observed that the curtain 50 may be drawn up tighter than would otherwise be possible, and that, consequently, the curtain may be draped to give a novel appearance. Still further, it will be noted that the curtain presents the same graceful folds whether the tie-back construction 22 is disposed on one side or the other thereof, and whether a strip of ornamental material 31 is used or not, either on the same side of the curtain as the tie-back construction 22 or on the opposite side thereof. And still further, it will be noted that the appearance of the folds is not marred in any way by exposure of the tie-back construction 22 to view.

If desired, as shown in Figure 7, the tie-back arrangement of the present invention may include an additional draw tape 24' which extends in closely spaced parallel relation to the tape 24, this additional tape being roved through and retained in position by its own warp knitted band 23'. The corresponding inner ends of both the tape 24' and its retaining band 23' are secured to the inner end of the curtain in the same manner as are the tape 24 and its band 23. In certain cases the band 23' may be warp knitted as an integral part of the band 24, the resultant structure being so formed as to provide a pair of

parallel courses through which, respectively, the two tapes may be roved as shown. By providing such double draw tape arrangement, the curtain may be easily drawn into and secured in draped condition by drawing the free ends of both tapes outwardly of the curtain and then tying them together, preferably into the form of a decorative bow knot.

In general, it will be understood that those skilled in the art may make changes in the details herein described and illustrated without departing from the spirit and scope of the invention as expressed in the appended claims. It is, therefore, intended that these details be interpreted as illustrative and not in a limiting sense.

What is claimed as new and useful is:

1. In a window curtain of the draped type comprising a body portion or panel of flexible material adapted to depend from a supporting member in a substantially ungathered condition with inner and outer edges extending generally vertically and a flexible tie-back construction comprising a draw tape and guiding means therefor extending across said panel from said inner to said outer edge, said guiding means including a band of material having a pair of spaced generally parallel runs and a plurality of relatively spaced additional runs each extending transversely between said parallel runs, said draw tape being roved through the openings between said spaced transversely extending additional runs and having an end portion secured to said inner edge of the panel, and said generally parallel runs being secured to said panel along their entire length.

2. In a window curtain of the draped type comprising a body portion or panel of flexible material adapted to depend from a supporting member in a substantially ungathered condition with inner and outer edges extending generally vertically and a flexible tie-back construction comprising a draw tape and guiding means therefor extending across said panel from said inner to said outer edge, said guiding means including a warp knitted band having a pair of spaced generally parallel headings and a plurality of relatively spaced groups of strands each extending transversely between said headings, said draw tape being roved through the openings between said spaced transversely extending groups of strands and having an end portion secured to said inner edge of the panel, and said generally parallel headings being secured to said panel along their entire length.

3. In a window curtain of the draped type comprising a body portion or panel of flexible material adapted to depend from a supporting member in a substantially ungathered condition with inner and outer edges extending generally vertically and a flexible tie-back construction comprising a draw tape and guiding means therefor extending across said panel from said inner to said outer edge, said guiding means including a warp knitted band having a pair of spaced generally parallel headings each formed by a warped strand rendered sinuous by additional chain stitched strands, and each having a loop of said warped strand at spaced portions therealong extending transversely therefrom and overlying the other of said headings to be secured thereto by said additional chain stitched strands associated therewith, said draw tape being roved through the openings between said spaced transversely extending loops and having an end portion secured to said inner edge of the panel, and said generally

parallel headings being secured to said panel along their entire length.

4. In a window curtain of the draped type comprising a body portion or panel of flexible material adapted to depend from a supporting member in a substantially ungathered condition with inner and outer edges extending generally vertically and a flexible tie-back construction comprising a draw tape and guiding means therefor extending across said panel from said inner to said outer edge, said guiding means including a warp knitted band having a pair of spaced generally parallel headings each formed by a warped strand having alternate groups of short and long loops rendered sinuous by additional chain stitched strands, said long loops being disposed to overlie the other of said headings to be secured thereto by said additional chain stitched strands associated therewith, said draw tape being roved through the openings between said groups of long loops and having an end portion secured to said inner edge of the panel, and said generally parallel headings being secured to said panel along their entire length.

5. In a window curtain of the draped type comprising a body portion or panel of flexible material adapted to depend from a supporting member in a substantially ungathered condition with inner and outer edges extending generally vertically and a flexible tie-back construction comprising a draw tape, guiding means for said draw tape, said guiding means and draw tape extending across said panel from said inner to said outer edge, said guiding means including a band

35 of material having a pair of spaced generally parallel runs and a plurality of relatively spaced additional runs each extending transversely between said parallel runs, said draw tape being roved through the opening between said spaced transversely extending additional runs, means

40 securing an end portion of said draw tape to said inner edge of the panel, and separate means securing said generally parallel runs to said panel along their entire length.

6. In a window curtain of the draped type comprising a body portion or panel of flexible material adapted to depend from a supporting member in a substantially ungathered condition with inner and outer edges extending generally vertically and a flexible tie-back construction comprising a draw tape, guiding means for said draw tape, said guiding means and draw tape extending across said panel from said inner to said outer edge, said guiding means including a band

55 of material having a pair of spaced generally parallel runs and a plurality of relatively spaced additional runs each extending transversely between said parallel runs, said draw tape being roved through the openings between said spaced transversely extending additional runs, stitches

60 securing an end portion of said draw tape to said inner edge of the panel, and separate stitches securing said generally parallel runs to said panel along their entire length.

7. In a window curtain of the draped type comprising a body portion or panel of flexible material adapted to depend from a supporting member in a substantially ungathered condition with inner and outer edges extending generally vertically and a flexible tie-back construction comprising a draw tape and guiding means therefor extending across said panel from said inner to said outer edge, said guiding means including a band of material having a pair of spaced generally parallel runs and a plurality of relatively

spaced additional runs each extending transversely between said parallel runs, said draw tape being rove through the openings between said spaced transversely extending additional runs so that the latter lay alternately against the inner and outer opposite faces of said draw tape and having an end portion secured to said inner edge of the panel, said generally parallel runs being secured to said panel along their entire length, and said panel and guiding means, except for the outer ones of said additional runs, folding on one side of said draw tape while the outer ones of said additional runs gather on the other side of said draw tape when the curtain is drawn, there being no bulk of material between said outer ones of said additional runs to resist said folding.

8. In a window curtain of the draped type comprising a body portion or panel of flexible material adapted to depend from a supporting member in a substantially ungathered condition with inner and outer edges extending generally vertically and a flexible tie-back construction comprising a draw tape and guiding means therefor extending across said panel from said inner to said outer edge, said guiding means including a warp knitted band having a pair of spaced generally parallel headings and a plurality of relatively spaced groups of strands each extending transversely between said headings, said draw

5 tape being rove through the openings between said spaced transversely extending groups of strands so that the latter lay alternately against the inner and outer opposite faces of said draw tape and having an end portion secured to said inner edge of the panel, said generally parallel headings being secured to said panel along their entire length, and said panel and guiding means except for the outer one of said groups of strands, 10 folding on one side of said draw tape while the outer ones of said groups of strands gather on the other side of said draw tape when the curtain is drawn, there being no bulk of material between said outer ones of said groups of strands to resist said folding.
